REFRIGERATOR CONDENSER COIL ASSEMBLY

Harold G. Dickman, Pleasant Ridge, Mich.

Application June 30, 1948, Serial No. 36,253

2 Claims. (Cl. 257—262.12)

1. This invention relates to condensers primarily useful in connection with mechanical refrigerators.

It has for its objects:

First, the production of a new and improved heat exchanger coil which is most efficient in operation and which can be made and assembled inexpensively.

Second, to provide such a coil which can be simply and easily assembled from rolled metal shapes which can be produced most inexpensively and which are particularly adapted for assembly into the coil to provide a wall construction, extra radiation surfaces for dissipating heat and a stack arrangement and flue action to assist in causing a circulation of air through the coil.

Third, to provide such a coil which can be made up as a unit and applied to a standard mechanical refrigerator cabinet in an inconspicuous manner and in such a way as to give highest efficiency in operation.

Other objects and advantages will be apparent from the following description of the invention, which is shown in the accompanying drawings, in which

Fig. 1 is a perspective view of a mechanical refrigerator with the improved coil installed thereon.

Fig. 2 is a perspective view of the coil assembly showing how the parts are assembled.

Fig. 3 is a detailed partial sectional view taken on the line 3, 3 of Fig. 2.

Fig. 4 is a perspective of the assembly taken from the opposite side of Fig. 2; and

Fig. 5 is a perspective view of one of the sheet metal units employed in making up the assembly.

The condenser unit which comprises this invention is made up of a coil, which can be a continuous serpentine coil, having a series of straight, parallel legs, between which are disposed hollow, open-end sheet metal members which provide heat dissipating surfaces and which, when disposed vertically, serve as stacks or flues which greatly increase the efficiency of the condenser by increasing the flow of the air past the heat transfer surfaces and the coils. The hollow tubular sheet metal members are formed from sheet metal strips cut to length, preferably by rolling. They are preferably so formed that each has a flat side which, in combination with the other flat sides, forms a continuous wall extending between the legs of the coil, thus providing an integral surface which may assist in confining the air to give flue action and which can be exposed when the unit is mounted on a refrigerator with-

out disfiguring the same, thus eliminating the necessity for any concealing walls. The sheet metal members are preferably slotted longitudinally to provide resiliency which materially aids in assembling the unit and in maintaining the tube and hollow sheet metal members in engagement during manufacturing and thereafter. The side walls of the hollow members are conformed to the tube so as to fit therearound so that when they are brazed or soldered together there will be adequate heat transfer from the tubes to the sheet metal members. In practice the assembly is mounted with the legs of the tube and the sheet metal members extending vertically. These members thus in effect become stacks or flues which assist in the circulation of the air and eliminate any eddy currents which might tend to slow down the flow of air past the coil.

In the drawings the unit is shown installed on a mechanical refrigerator 1, which is shown in a back perspective view, with the coil assembly fastened to the back wall 2 of the cabinet, which is indicated generally at 3.

The condenser consists of a series of straight, parallel legs 5, which are shown as part of the serpentine tube 4, which is here shown as continuous.

Between adjacent, parallel legs 5 are inserted the open-end sheet metal members 6. These members are preferably cut to the length desired for any given assembly and then formed by rolling. Each member has a flat base 7 which, with the flat bases 7 of the other members, forms a continuous wall 8 extending between the legs 5 of the tube 4. Side walls 9 extend from the base 7. Near the base 7 each side wall is formed with a half-round 10 to fit the legs 5 of the tube. The side wall then extends away from the base as shown at 11 in Figs. 3 and 5, to a central longitudinal slot 12 forming a substantially closed tube which is open at its ends and which in the vertical position serves as a stack with the walls serving as heat transfer surfaces.

The longitudinal slot provides resiliency in the sheet metal members so that they can be easily assembled in the unit by sliding them between the legs 5. How this is done is indicated in Fig. 2, the arrow showing the direction in which the sheet metal members are pushed for assembly.

The assembled tubes and sheet metal members are joined by brazing or soldering, as indicated at 13. A suitable supporting frame consists of a series of metal straps 14 to which the flat bases 7 are attached as by spot welding, as indicated at 15. Bracket members 16 are provided for at-

taching the assembly to the rear wall 2 of the cabinet. These members are provided with flanges 17, which are fastened to the members 14 by means of machine screws 18 and flanges 19, which are fastened to the back of the cabinet by screws 20.

The unit is assembled on the box, as shown in Fig. 1, with the legs of the tube 4 extending vertically and with the sheet metal members 6 likewise extending vertically.

The back 8 is disposed upwardly and the near-extending side members 11 of the sheet metal members 6 extend toward the wall of the cabinet. They are thus protected and concealed and are held in spaced relationship from the rear wall of the cabinet providing an air space through which air can circulate. The circulation is caused by convection and the air passing upwardly through the unit and the flues or stacks eliminates the heat from the condenser and efficiently cools the unit.

The unit can be manufactured simply and inexpensively because of the nature of the sheet metal members 6 which can be cut to length, then formed by rolling and then assembled, making it possible to assemble any desired size of unit depending upon the length of tube bent into the serpentine form.

The condenser is highly efficient in operation. It is possible to run under very high back pressures and at very high temperatures with cooling to lower temperatures.

The preferred form of the invention has been described above. It will be apparent to those skilled in the art that the condenser of this invention may be changed in form without departing from this invention. Although the preferred form has been described, there is no intention of limiting the invention to this form, it being intended only that the invention be limited to that covered by the claims.

I claim:

1. A condenser unit comprising a continuous serpentine tube having a series of spaced straight parallel legs interconnected by bights in the tube and having fitted between said legs and in contact therewith for substantially their entire length a series of nonintegral sheet metal members each comprising a substantially flat base, which, with the bases of adjacent members, forms a flat wall section joining said legs and each member having side walls extending from the sides of the base and substantially perpendicular thereto

and adjacent the legs, said walls being shaped near the base to fit around the adjacent leg and extending between the legs and beyond the plane thereof to form hollow flues parallel to said legs, the free edges of said walls extending into proximity to one another but being unconnected whereby said wall members may be flexed on insertion between legs to conform to irregularities in said serpentine tube to establish and maintain contact between each of said walls and the adjacent leg throughout the length of said wall without deforming said tube.

2. A condenser unit comprising a continuous serpentine tube having a series of spaced straight parallel legs interconnected by bights in the tube and having fitted between said legs and in contact therewith for substantially their entire length a series of nonintegral sheet metal members each comprising a substantially flat base, which, with the bases of adjacent members, forms a flat wall section joining said legs and each member having side walls extending from the sides of the base and substantially perpendicular thereto and adjacent the legs, said walls extending between the legs and beyond the plane thereof to form hollow flues parallel to said legs, the free edges of said walls extending into proximity to one another but being unconnected whereby said wall members may be flexed on insertion between legs to conform to irregularities in said serpentine tube to establish and maintain contact between each of said walls and the adjacent leg throughout the length of said wall without deforming said tube.

HAROLD G. DICKMAN.
